CLAIM

The ornamental design for a food frame, as shown and described.

DESCRIPTION

FIG. 1 is an exploded perspective view of a food frame, showing my new design;

FIG. 2 is a front elevational view of the invention, the rear elevational view being a mirror image thereof;

FIG. 3 is a left-side elevational view of the invention, the right-side elevational view being a mirror image thereof;

FIG. 4 is a top plan view of the invention; and,

FIG. 5 is a bottom plan view of the invention.

The broken lines showing a food serving pan in FIG. 1 are included for the purpose of illustrating the invention in use, and form no part of the claimed design.

1 Claim, 2 Drawing Sheets

FIG. 1

FIG. 2
